REPEATER FOR PHONOGRAHS

Joseph Louis Routin, Paris, France

Application March 27, 1939, Serial No. 264,431
In France June 8, 1938

6 Claims. (Cl. 274—14)

The invention relates to sound reproducing apparatus and more particularly to the application of such apparatus to the study of, say, foreign languages by utilization of the two main principles of subdividing and repeating. The principal object of the invention is to provide an apparatus which renders it possible on the one hand to interrupt suddenly the audition of a record at any desired moment and for any desired period and, on the other hand, to insure that the audition can be taken up again at any predetermined point on the record. It is a further object to provide apparatus of this class which can be readily adapted to sound reproducing machines generally and this with a minimum of modification of such machines so that it can readily be applied to all types of existing machines.

Simplicity, ease of manufacture, long life and low cost are other objects attained by the apparatus forming the subject of the invention.

These objects are attained by providing a device for use with a sound reproducing machine which renders it possible to obtain the repetition of any part of a sound record, such device comprising a thin, narrow strip extending across the record substantially at right angles to the sound grooves therein and provided with guiding means cooperating with parts on the reproducer or pick-up of the machine to enable, by the proper manipulation of the strip, the sound box and needle to be lifted off the record to stop the audition, to be returned to the starting position for the repetition of a desired passage, and to be returned to playing position on the record without shock to repeat the desired passage, all this being possible while the motor is running.

The strip is also provided with fine adjustment means for adjusting it in the direction of its length and with means for supporting it in its raised position with the needle lifted off the record or in its lowered playing position.

Other and further objects and advantages and the means by which they are attained will become apparent from the following detailed description when read in connection with the accompanying drawings forming a part of this specification.

In the drawings:

Fig. 1 is a fragmentary perspective view of a sound reproducing machine equipped with the device according to one form of the invention.

Fig. 2 is a fragmentary plan view on an enlarged scale of the device as shown in Fig. 1.

Figs. 3 and 4 are similar side elevational views,

parts being shown in section, Fig. 3 showing the parts in the playing position and Fig. 4 showing the parts in a position interrupting the audition.

Fig. 5 is a bottom plan view of the inner end portion of the repeater strip.

Figs. 6 and 7 are fragmentary sectional elevations taken, respectively, on the lines 6—6 and 7—7 of Fig. 5.

Fig. 8 is a fragmentary elevational view, parts being shown in section, of a form of guide and support for the outer end of the repeater strip.

Fig. 9 shows in side elevation, parts being in section, a modified form of support for the outer end of the strip.

Fig. 10 is a similar view of a third modification of the support.

Fig. 11 is a side elevational view similar to Fig. 3 and 4, except that it is taken from the opposite ends of the reproducer, showing a modified form of supporting arm applied to the reproducer.

In the drawings, the invention is shown applied to a sound reproducing machine of the rotating disc type in which the casing or cabinet of the machine is designated by the numeral 10, the revolving table by 11, the record disc by 12, the transversely swinging tone arm by 13, the liftable reproducer or sound box by 14, the driving spindle by 15, indicated by dotted lines in Fig. 2, all of these parts being of any usual or known form.

With the sound box 14 is associated a lifting arm 16, which, in the form of the invention shown in Figs. 1 to 4, may form part of a needle assembly unit consisting of a block 17, having a needle 18 clamped within an opening therein by the clamping screw 18'. The lifting arm 16 may comprise a bent rod fixed to the block 17 and having a straight portion 19 projecting upwardly therefrom which may extend into the usual needle receiving opening on the reproducer and be clamped therein by the usual clamping screw 20. It will be understood that the needle assembly is located with respect to the usual needle receiving socket on the reproducer in a definite fixed angular relation, so that the needle and lifting arm will always be in their proper cooperative relation to the repeater strip now to be described.

The repeater strip is designated generally by the reference character R and forms the main element of the invention. As shown, it may consist of a thin metallic strip 21 having at its widened inner end and an opening 22, within which is rotatably mounted an adjusting button 23 having a graduated scale 24 thereon cooperating with a

fixed index 25 on the strip 21, see Fig. 2. The button 23 is preferably held by light friction from rotating in the opening 22. Shoulders 26 and 27 and a stop screw 28 preferably limit the rotation of the button to a predetermined arc, see Fig. 5. For convenience in manufacture the button 23 may have its pivot portion and its body portion made separately and secured together and to the strip 21 by screws as 29.

To space the end of the strip from the record the pivot portion of the button is provided with a shallow boss 30, this boss being located eccentrically with respect to the axis of rotation of the button and, concentric with this boss, the button is provided with an opening 31 adapted to fit the driving spindle 15 of the machine. To allow a slight lifting of the free end of the strip 21 for a purpose to be described, the opening 31 is preferably tapered or otherwise formed (not shown) to prevent binding with the spindle.

The strip 21 for the width of the playing portion of the record is formed on what may be termed its forward edge, having regard to the direction of rotation of the record as indicated by the arrow J in Fig. 2, with a series of V notches formed by projections A, B, C, etc. This forward edge of the strip through this notched region is preferably curved on an arc corresponding to the arc described by the needle in moving from the outer margin to the inner of the playing portion of the record. The strip is normally arranged generally parallel to this arcuate path and in close adjacency to said path of the needle, so that the lifting arm 16 has its free end, in all playing positions of the reproducer, disposed above the strip. Opposite the series of notches formed by projections A, B, etc., the strip is formed with a corresponding series of grooves a, b, c, etc., closed at the bottom and cooperating with the series of notches A, B, C in a manner to be described in guiding the needle to the starting position of the audition.

For convenience of manufacture the notches and grooves may be formed on a separate metallic strip 32 which is suitably fastened as by screws 33 to the top of the strip 21.

To locate and guide the free end of the strip 21 which preferably projects a considerable distance beyond the record to provide a handle portion 34, there is arranged between the handle portion and the cabinet a supporting and guiding strip 35 having, in this instance, an upstanding portion 36 provided with a horizontal slot 37 and a base flange 38 through which it may be secured to the cabinet 10 as by screws 39. The slot 37 is deepened vertically at one end so that the bottom of the slot forms a low portion 40 and a high portion 41 corresponding to the portions shown respectively in Figs. 3 and 4.

To stabilize the strip laterally and to avoid tipping of the same, it is provided at its inner end on the side opposite the boss 30 with block 42 having rounded ends and of a depth approximately equal to the depth of the boss. This block is faced with a soft yielding material, such as leather, to avoid marring the record and may be secured by a screw 43 to strip 21.

The eccentricity of the mounting of the button 23 and the degree of its angular movement is preferably such that the endwise displacement of the slide may be slightly greater than the distance between two projections A, B, C, etc. It will be seen that the adjusting button

thus provides for very accurately determining the starting point of an audition.

In such longitudinal adjustment of the slide while the record is playing and the slide therefore rests at the low portion 40 of the slot 37, it is desirable that the angular relation of the slide to the record be maintained and to this end the slide is guided at its outer end through the curved side edge portions 44 and 45, see Fig. 2, between the side walls of the low portion of the slot.

The operation of the device will now be briefly described. With the free end of the slide resting on the high portion of the slot 41 of the supporting and guiding plate 35 and the sound box held in the raised position with the needle off the record, as shown in Fig. 4, through the engagement of the lifting arm 16 with the top of the repeater strip R, and the needle projecting into the desired notch on the forward edge of the repeater strip, the free end of the strip is grasped by the hand and moved to the vertically deep portion of the slot and then gradually lowered to rest on the portion 40. In this lowering movement the needle is lowered on the record as shown in Fig. 3 and the audition is commenced. While the audition is taking place, the strip R is held slightly raised above the surface of the record by the three-point support afforded by boss 30, block 42 and low portion 40 of the slot in the supporting strip 35, so as to avoid marring the record or retarding its rotation. At this time also the end of the lifting arm 16, while located above the strip, is slightly spaced therefrom, as shown in Fig. 3.

If the audition is now desired to be suspended before the needle has travelled beyond the selected notch in the strip R, the operator grasps the handle portion 34 of the strip and lifts it thus lifting the needle off the record, as shown in Fig. 4. By then moving the strip into the high portion 41 of the slot 37, the V-notch opposite the needle guides the needle to the bottom of the notch, but before this takes place the end of the lifting arm drops into the V-groove opposite the given notch and this V-groove then guides the arm, when the strip R is moved in the opposite direction, to deposit the needle on the record at the starting point, when the strip is again lowered to the position shown in Fig. 3. Thus the same passage may be repeated as often as desired by simply repeating this operation.

If it is desired to start the audition a few words or a sentence earlier, this can be done by turning the adjusting button 23 the desired amount and thus advancing the point at which the needle is again lowered on the record, by the amount of the adjustment.

It will be understood that the sound box and needle may be swung along the repeater strip R to any desired point on the record at any time while the parts are in the position shown in Fig. 3, but with the strip raised to lift the needle off the record, the end of the lifting arm 16 then sliding along the repeater in the space between the series of notches and grooves.

Thus it will be seen that any selected part of the record may be repeated by the simple operations above described.

In Fig. 9, is shown an alternative means to that shown in Fig. 8 for holding the free end of the strip 21 in lowered position corresponding to the position shown in Fig. 3 and for adjusting this position as desired, for example, to adapt the de-

vice to different machines or different thickness of records. This means may comprise a screw threaded rod 46 threaded through a threaded opening 47 in strip 21, the lower end of this rod being provided with a foot piece 47' which is adapted to rest on the side wall 48 of the cabinet 49. To facilitate the adjustment of the screw rod, the outer periphery of the foot piece may be knurled (not shown). A nut 49 is screwed on the upper end of the rod 46 to limit the height of the raised position of the repeater strip. This nut can remain fixed once the device has been adjusted for the proper height.

In Fig. 10 is shown a still further modification of the supporting and guiding means for the free end of the strip 21. In this case, a slotted vertical plate 50 is supported from the top of the cabinet 10 through links 51 and 52 pivoted respectively to the ends of the plate and to brackets 53 and 54 secured to the top of the cabinet. Stop pins 55 on bracket 54 limit the movement of the link 52 and link 51 is extended to form a handle 56 through which the plate can be readily moved from one position to the other to raise and lower the strip 21 which extends through the slot in the plate 50. The slot is shown wider than the strip and the strip is yielding held at one end of the slot by a light spring 57 operating through a U-shaped slide 58 upon the strip, the slide 58 being guided in brackets 59 on plate 50. This form of the device lends itself to automatic operation, for by using a cam governed by the motor of the talking machine for actuating the lever 56, any number of repetitions could be automatically effected. Such an automatic control is shown and described in my co-pending application Serial No. 108,987. The lever could also be operated by some other form of remote control not governed by the motor of the machine.

In Fig. 11 is shown an alternative to the form shown in Figs. 1, 3 and 4, for lifting the sound box 14. In this case, an angular lifting arm 60 which may be of sheet metal, is secured through one of its arms to the side of the sound box 14 as by screws 61, its other arm having its free end arranged opposite the usual needle 18 of the sound box in position to cooperate with the needle in guiding the same through their cooperation with the V notches and grooves hereinbefore described.

While a specific form of the device and several modifications have been herein described, it will be understood that further modifications may be made by those skilled in this art without departing from the spirit and scope of the claims appended hereto.

What I claim is:

1. In a repeater device to be used with a sound reproducing machine including a casing, a driven

5 rotary table supported thereby on a vertical spindle having its upper end projecting above the table, a record disc having a central hole therethrough and a spiral sound track on the face thereof supported on said table for rotation therewith, a reproducer carrying a needle for engagement with the sound track of the record, said reproducer and needle being mounted on said casing for horizontal movement across the face 10 of the record and for vertical movement to raise the needle off the record, the combination of a lifting rod secured to the reproducer and having its free end located some distance above the record, and a thin narrow strip extending lengthwise generally parallel to the path of movement of said needle and under the end of the lifting rod, said strip being longer than the radius of said disc, one end of said strip having a socket therein into which the spindle of said rotary table is 15 adapted to extend and the other end being formed as a handle to be grasped by the operator, said strip having a series of transverse generally radially outwardly inclined grooves formed in its upper face, means associated with the socketed end of the strip for adjusting the distance of the grooves from the socket at will, said grooves co-operating with the lifting rod when the handle of the strip is raised and the strip swung about its pivot to first lift the needle off the record 20 and then move it backward.

2. In a repeater device according to claim 1 in which the edge of the strip adjacent the needle has a series of notches of generally V-shape separated from the grooves by a smooth portion and so located that they cooperate with the needle to aid in moving the needle backward.

3. In a repeater device according to claim 1 in which the lifting rod forms parts of a needle assembly unit comprising a block having a needle 35 clamped therein.

4. In a repeater device according to claim 1 in which the means for adjusting the distance of the grooves from the socket at will comprises an eccentric device the amplitude of rotation of 40 which is limited by two stops.

5. In a repeater device according to claim 1 in which the strip is provided adjacent its pivoted end with a laterally spaced support arranged so that the line joining it with the pivot lies always approximately at right angles with the longitudinal axis of the strip.

6. In a repeater device according to claim 1 in which the casing of the machine carries a guiding and supporting member cooperating with the handle end of the strip, said member having two support portions at different levels, one supporting the strip when the needle is in operative relation to the record and the other when the needle is raised off the record.

JOSEPH LOUIS ROUTIN.
